D. MURRAY.

Dry Measure.

No. 25,212.

Patented Aug. 23, 1859.

UNITED STATES PATENT OFFICE.

DANIEL MURRAY, OF FAIRFIELD, NORTH CAROLINA.

MODE OF MEASURING GRAIN.

Specification of Letters Patent No. 25,212, dated August 23, 1859.

To all whom it may concern:

Be it known that I, DANIEL MURRAY, of 5
Fairfield, in the county of Hyde, in the State
of North Carolina, have invented a new and
Improved Mode of Measuring Grain; and I
do hereby declare that the following is a
full and exact description thereof, reference
being had to the accompanying drawings,
and to the letters of reference marked
10 therein, in which—

Figure 1 is a side elevation and Fig. 2 an
end elevation.

The nature of my invention consists in the
movable slides for cutting off the grain as
hereinafter described.

To enable others skilled in the art to make
and use my invention I will proceed to de-
scribe its construction and operation.

In the construction of my invention in
20 Fig. 1, A is the frame. B is the hopper. C
is the box in which the grain is measured.
D is the discharge; a, the upper arm; b, the
upper slide. Fig. 2, d, the levers connecting
the slide with the arms and which operate
25 on points as a hinge joint or cut off; E, the
middle guard in which the arm operates; F,
an upper guard to which it may be placed
when moved up; h, the lower arm; f, the
lower slide or cut off; G, the lower guard in
30 which the arm operates; I, slots in box C
for the slides to operate in. K is the ful-
crum of the arms which is attached to frame
A; l l, washers between the arms a and h.
The upper may be moved up to make the
35 arms farther apart when necessary as here-
inafter described; m, keys for keeping the

front pieces of the frame which are movable
in their places or on their tenons.

In Fig. 2 like parts are described by same
letters.

In operating my machine, when I com-
mence to measure grain I remove the upper
slide to let the grain in the hopper C till the
box is filled above the upper slide or cut off
and then the upper slide is pushed in and
remains till the lower slide is removed and
grain discharged when it is returned to its
place. When I wish to measure double the
40 quantity I remove the rod constituting the
fulcrum, out of the arms, then remove the
upper arm and slide and place them in the
upper slot I and guard F and then place
the washer below the arm a—and then place
the rod or fulcrum as before when it is ready
45 to operate measuring twice the quantity.
The dotted lines show the operation of the
slides in box C. The arm is connected with
the slide by two joints which allows the
50 slides to run in a direct line in box C.

Having thus described my invention, what
I claim and desire to secure by Letters Pat-
ent is—

The arrangement of the arms a and h in
combination with the slides b and f con-
structed and operating as described and for
65 the purposes set forth.

DANIEL MURRAY.
